ABSTRACT OF THE DISCLOSURE

Orthoferrite single crystals are produced by first producing an orthoferrite polycrystalline body having an Fe_2O_3 content ranging from about 49.8 mol percent to 50.4 mol percent and then subjecting said body to a floating-zone method in oxygen at a pressure ranging from 1 to 10 atmospheres.

The present invention relates to a method of preparing orthoferrite single crystals by the floating-zone method.

The chemical formula of orthoferrite is $RFeO_3$ where-
in R denotes an element selected from the group consist-
ing of yttrium and rare earth elements. Complex ortho-
ferrite, such as of the formula $R_{1-x}R'_xFeO_3$, wherein R
and R' both denote yttrium or one of rare earth elements
and which is obtainable by replacing a part x of R in
 $RFeO_3$ with another element R', is meant to be included
in the term "orthoferrite." Recent uses of orthoferrite
single crystals have been in cylindrical domain device
applications.

Various methods, such as the flux method and hydro-
thermal synthesis, are known for producing orthoferrite
single crystals. However, with such methods, the growth
of single crystals is too slow and large single crystals are
not obtainable. It would be desirable to provide a floating-
zone method for producing large single orthoferrite
crystals.

It is known that single crystals may be produced by the
floating-zone method, providing that the object compound
crystallizes as a solid phase congruently. This requirement
is satisfied by orthoferrites of stoichiometric composition,
that is, consisting of 50 mol percent Fe_2O_3 and 50 mol
percent R_2O_3 .

Where the compositions of orthoferrites are slightly
different from the stoichiometric composition and tend to-
wards an excess of the iron component or an excess of
the rare earth component, the floating-zone method is
hardly useful in the manufacture of single crystals there-
of. Since marked or significant changes in magnetic do-
main structure and other magnetic properties of the single
crystal do not readily occur, it is possible to employ
single crystals of such compositions in practical applica-
tions. Generally, when the composition varies from the
stoichiometric composition, gas bubbles develop in or de-
rive from the molten zone, as will be discussed later, such
that a stable molten zone is not formed. This interrupts
the stable growth of single crystals. In addition, numerous
spherical pores remain in the single crystal grown under
such conditions. Thus, a homogeneous single crystal is not
obtainable with such compositions.

Because of the foregoing problems, it is generally re-
quired that the polycrystalline raw material employed for
producing a single crystal be stoichiometric in composi-
tion. However, this has economic disadvantages in com-
merce insofar as yield and productive efficiency are con-
cerned.

Generally speaking, iron oxides and oxides of yttrium
and other rare earth metals (including the metal salts and

metal hydroxides which are capable of being converted
into oxides at higher temperatures) used as starting ma-
terials for making orthoferrites are usually hygroscopic
and difficult to control with regard to the metallic con-
tents thereof. Moreover, it is difficult to regulate amounts
of iron picked up in ball mills and other impurities which
are absorbed in the process of preparing a polycrystalline
raw material. Therefore, it is very difficult to prepare
polycrystalline raw material of homogeneous composition

5 in which the molar ratio of Fe_2O_3 to R_2O_3 has the de-
sired stoichiometry. The actual composition usually falls
within the range of 50 ± 0.5 mol percent of Fe_2O_3 . When
a single crystal is prepared according to the floating-zone
10 method from polycrystalline raw material whose compo-
sition varies or deviates to some extent from the stoichio-
metric composition, then bubbles are formed depending
upon the amount of deviation from the stoichiometric
15 composition within the molten zone, the bubbles there-
after coagulating and gradually growing into large
bubbles in the molten zone. Finally, they escape from the
molten zone and vanish. When this process is repeated in
20 the course of the crystal growth, the molten zone which
should otherwise be stable undergoes shock and, in ex-
treme cases, the molten zone is broken.

25 It is therefore an object of the present invention to
provide a method of making homogeneous orthoferrite
single crystals by the floating-zone technique at an im-
proved yield rate, even where there are slight differences
30 in compositions among polycrystalline raw materials and
where the compositions of the raw materials deviate from
stoichiometry.

According to the invention, crystal growth by the float-
ing-zone method using polycrystalline raw material is car-
ried out in an oxygen-containing atmosphere, e.g. air or
35 in an atmosphere of oxygen, at one to ten atmospheric
pressure, depending upon the deviation of the compo-
sition of the polycrystalline raw material from the stoichio-
metric relationship of the compound of orthoferrite.

Optimum atmosphere is determined by the compo-
40 sition of the polycrystalline raw material. Where the raw
material contains just 50.0 mol percent Fe_2O_3 , oxygen of
at least one atmospheric pressure (atm.) can be used.
Where the Fe_2O_3 content of the raw material deviates
45 from 50.0 mol percent by x mol percent, oxygen having
 $(20|x|-1)$ or more atmospheric pressure should be used
as an atmosphere during crystal growth by the floating-
zone method using the raw material. However, the pres-
sure should not exceed 10 atmospheres as oxygen pres-
50 sure more than 10 atmospheres often produces an abnor-
mal projection in part of polycrystalline raw material in
contact with the molten zone and makes the molten zone
unstable. Therefore pressures above 10 atmospheres
should be avoided. Furthermore, if the deviation of the
55 composition of polycrystalline raw material is so large
that the Fe_2O_3 content thereof lies outside the range of
49.8 mol percent to 50.4 mol percent, then a different
phase other than orthoferrite may tend to deposit. There-
fore, compositions outside the foregoing range should be
60 avoided.

According to the invention, by utilizing a single crystal
growth furnace for the floating-zone method in which the
atmosphere is optionally controllable, the yield rate in
the manufacture of such crystals is markedly improved.

65 As illustrative of the invention, the following preferred
embodiments are given.

EMBODIMENT 1

Feed rods of polycrystalline raw materials of $YFeO_3$
70 were prepared by the usual method of making ferrite cer-
amics. A feed rod was placed in a floating-zone appa-
ratus. A molten zone was formed between the feed rod

and a seed crystal by heating to a temperature above the melting point (about 1700° C.) of YFeO_3 , and the zone moved upward at a constant rate. The feed rod and the seed crystal were rotated at 30 r.p.m. in the opposite direction in order to produce a good stirring action and reduce temperature gradients. The direction of growth was generally parallel to the c-axis.

Experiments on crystal growth of YFeO_3 were carried out in an oxygen atmosphere having oxygen pressures of 1 to 10 atm. and at a growth rate of about 10 mm./hr. by using feed rods having compositions of 49.5 to 50.7 mol percent Fe_2O_3 . Experimental results particularly relating to gas bubble derivation from the molten zone and other phase precipitation in the crystals are shown in Table 1.

TABLE 1

Sample number	Composition ¹		Oxygen pressure (atm.)	Gas bubble derivation ²	Other phase precipitation ²
	Fe_2O_3 (mol percent)	Y_2O_3 (mol percent)			
1	49.5	50.5	1	Yes	Yes
2	49.5	50.5	10	Yes	Yes
3	49.8	50.2	1	Yes	No
4	49.8	50.2	3	No	No
5	50.1	49.9	1	No	No
6	50.1	49.9	10	No	No
7	50.3	49.7	1	Yes	No
8	50.3	49.7	4	Yes	No
9	50.3	49.7	6	No	No
10	50.3	49.7	10	No	No
11	50.4	49.6	5	Yes	No
12	50.4	49.6	7	No	No
13	50.7	49.3	1	Yes	Yes
14	50.7	49.3	10	Yes	Yes

¹ Composition is that of feed rod before sintering and determined by the chemical analysis.

² Yes denotes that the phenomena were more or less observed and No denotes not observed.

As will be seen from Table 1, gas bubble derivation decreases with the decrease of the deviation of feed rod composition from stoichiometry and with the increase of oxygen pressure. In the case of nearly stoichiometric composition (Sample Nos. 5 and 6), no gas bubble derivation was observed, whether under 1 oxygen atmospheric pressure or under a higher oxygen pressure of ten atmospheres whereby smooth crystal growth was obtained. Where the YFeO_3 feed rod has an excess Fe_2O_3 content by about 0.3 mol percent above stoichiometry (Sample Nos. 7 to 10), gas derivatives from the molten zone under 1 atmosphere, while gas derivation does not occur under a higher oxygen pressure of 6 atm. or more. Where the deviation increases up to 0.4 mol percent Fe_2O_3 excess (Sample

45

phases can be produced if x satisfies the relationship $-0.2 \leq x \leq 0.4$. In this case, if $|x| \leq 0.1$, no gas bubble is derived from the molten zone under 1 atm. oxygen pressure. If $|x| > 0.1$, no gas bubble derivation occurs under an oxygen pressure of $(20|x| - 1)$ atmospheres or more.

Although the growth rate was 10 mm./hr. in the above experiments, results did not vary under a growth rate of 3 mm./hr. to 20 mm./hr.

EMBODIMENT 2

By using the same technique as Embodiment 1, single crystals of TbFeO_3 , ErFeO_3 and YbFeO_3 were grown. Typical results are shown in Table 2. High oxygen pressure of $20|x| - 1$ or more atmospheres is also effective in these cases, as is seen from Table 2.

TABLE 2

Sample number	Composition ¹		Oxygen pressure (atm.)	Gas bubble derivation ²	Other phase precipitation ²
	Fe_2O_3 (mol percent)	R_2O_3 (mol percent)			
15	50.2	Tb_2O_3 , 49.8	1	Yes	No
16	50.2	Tb_2O_3 , 49.8	7	No	No
17	50.3	Er_2O_3 , 49.7	1	Yes	No
18	50.3	Er_2O_3 , 49.7	8	No	No
19	49.9	Yb_2O_3 , 50.1	1	No	No
20	50.3	Yb_2O_3 , 49.7	1	Yes	No
21	50.3	Yb_2O_3 , 49.7	7	No	No

NOTE.—See footnotes 1 and 2 at end of Table 1.

EMBODIMENT 3

Sample Nos. 22 to 24 of Table 3 show that the invention is also effective for YFeO_3 in which Fe is partially replaced with Co^{3+} . Since Co occupies the site of Fe in the crystal lattice, the stoichiometric composition of the raw material in this case is 50 mol percent Y_2O_3 and 50 mol percent in total of Fe_2O_3 plus Co_2O_3 . Co^{3+} may replace up to 5 atomic percent of Fe. Sample No. 25 of Table 3 represent that the invention can be successfully applied to production of YFeO_3 in which part of Fe is replaced with Co^{2+} and Ti^{4+} . Since Co and Ti occupy the sites of Fe ions in the crystal, the stoichiometric composition of the raw material is 50 mol percent Y_2O_3 and 50 mol percent in total of Fe_2O_3 , CoO and TiO_2 in this case. Co and Ti may replace up to 5 atomic percent of Fe. Where the feed rod composition $\text{Fe}_2\text{O}_3 + \text{Co}_2\text{O}_3$ or

is $50+x$ mol percent, the floating-zone melting under an oxygen pressure of $20|x| - 1$ atm. or more can produce good single crystals.

TABLE 3

Sample number	Composition ¹ (mol percent)			Oxygen pressure (atm.)	Gas bubble derivation ²	Other phase precipitation ²
	Fe_2O_3	Co_2O_3	Y_2O_3			
22	49.8	0.3	50.0	1	No	No
23	50.1	0.3	49.6	1	Yes	No
24	50.1	0.3	49.6	10	No	No
25	49.8	$\text{CoO} + \text{TiO}_2$, 0.2	50.0	1	No	No

NOTE.—See footnotes 1 and 2 at end of table 1.

Nos. 11 and 12), still high oxygen pressure of 7 atmospheres or more is necessary to stop gas bubble derivation. If the feed rod composition deviates toward the Y_2O_3 excess side by 0.2 mol percent from the stoichiometry (Sample Nos. 3 and 4), a higher oxygen pressure of 3 or more is needed. On the other hand, application of oxygen pressure cannot stop gas bubble derivation and precipitation of other phases than orthoferrite in the resultant single crystal, if the deviation of the composition is too large (Sample Nos. 1, 2, 13 and 14).

The deviation of feed rod composition from the stoichiometry and the oxygen pressure necessary to stop the gas bubble derivation appears to have nearly a linear relationship. Summarizing the foregoing, where the Fe_2O_3 composition of polycrystalline raw material is expressed by $50+x$ mol percent, single crystals having no other

Although the present invention has been described in conjunction with preferred embodiments, it is to be understood that modifications and variations may be resorted to without departing from the spirit and scope of the invention as those skilled in the art will readily understand. Such modifications and variations are considered to be within the purview and scope of the invention and the appended claims.

What is claimed is:

1. A method of producing orthoferrite single crystals comprising the steps of preparing an orthoferrite polycrystalline body consisting essentially of Fe_2O_3 and one oxide selected from the group of Y_2O_3 , Tb_2O_3 , Er_2O_3 , and Yb_2O_3 , the Fe_2O_3 content being $50+x$ mol percent with x ranging from -0.2 to $+0.4$, and subjecting said polycrystalline body to floating zone melting by heating said

polycrystalline body at a temperature higher than the melting point of said polycrystalline body to form a molten zone between said polycrystalline body and a seed crystal and moving said molten zone at a rate of 3 to 20 mm. per hour in an oxygen atmosphere having a pressure of at least one atmospheric pressure where $|x| \leq 0.1$ and at least $20|x|-1$ atmospheric pressure where $|x| > 0.1$, the pressure of said atmosphere being not more than ten atmospheric pressure.

2. The method claimed in claim 1, in which the oxide is Y_2O_3 .

3. A method of producing orthoferrite single crystals comprising the steps of preparing an orthoferrite polycrystalline body consisting essentially of Fe_2O_3 and one oxide selected from the group of Y_2O_3 , Tb_2O_3 , Er_2O_3 , and Yb_2O_3 , wherein an amount ranging up to 5 atomic percent of Fe is replaced by Co^{3+} as Co_2O_3 , and wherein the Fe_2O_3 and the Co_2O_3 content is $50+x$ mol percent with x ranging from -0.2 to +0.4, and subjecting said polycrystalline body to floating zone melting by heating said polycrystalline body at a temperature higher than the melting point of said polycrystalline body to form a molten zone between said polycrystalline body and a seed crystal and moving said molten zone at a rate of 3 to 20 mm. per hour in an oxygen atmosphere having a pressure of at least one atmospheric pressure where $|x| \leq 0.1$ and at least $20|x|-1$ atmospheric pressure where $|x| > 0.1$, the pressure of said atmosphere being not more than ten atmospheric pressure.

4. The method claimed in claim 3, in which the oxide is Y_2O_3 .

5. A method of producing orthoferrite single crystals comprising the steps of preparing an orthoferrite polycrystalline body consisting essentially of Fe_2O_3 and one

oxide selected from the group of Y_2O_3 , Tb_2O_3 , Er_2O_3 , and Yb_2O_3 , wherein an amount ranging up to 5 atomic percent of Fe is replaced by a combination of Co^{3+} and Ti^{4+} as CoO and TiO_2 and wherein the Fe_2O_3 , the CoO and the TiO_2 content is $50+x$ mol percent with x ranging from -0.2 to +0.4, and subjecting said polycrystalline body to floating zone melting by heating said polycrystalline body at a temperature higher than the melting points of said polycrystalline body to form a molten zone between said polycrystalline body and a seed crystal and moving said molten zone at a rate of 3 to 20 mm. per hour in an oxygen atmosphere having a pressure of at least one atmospheric pressure where $|x| \leq 0.1$ and at least $20|x|-1$ atmospheric pressure where $|x| > 0.1$, the pressure of said atmosphere being not more than ten atmospheric pressure.

6. The method claimed in claim 5, in which the oxide is Y_2O_3 .
